FUSE FOR PROJECTILES

Harold G. Towner, New Haven, Conn.

Application June 24, 1936, Serial No. 87,017

5 Claims. (CL 102—39)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a fuse for projectiles. The purpose of the invention is to provide a bore safe fuse especially adapted for a projectile that is to be fired from a smooth bore mortar. This is accomplished by a simple and inexpensive arrangement in which a cap holding the firing mechanism in safe position is removed after the projectile leaves the bore of the gun.

To these and other ends, the invention consists in the construction, arrangement and combination of elements, described hereinafter and pointed out in the claims forming a part of this specification.

A practical embodiment of the invention is illustrated in the accompanying drawing which is 20 a longitudinal sectional view of the improved fuse with the parts in unarmed or safe position.

Referring to the drawing by characters of reference, the fuse casing comprises a body 5 having a reduced rear end 6 whereby it is threadedly attached to a projectile 7. A cup 8 threadedly carried by the rear end of the fuse body is disposed within the projectile and contains a booster charge 9.

The fuse body 5 is formed with an axial passage 30 10 and an intersecting transverse passage 11. A carrier comprising a bolt 12 carrying a primer detonator 13 is formed with an aperture 14 for receiving the inner end of a firing pin 15 disposed in the upper or outer portion of the axial passage 35 10. The firing pin, when received in the aperture 14, holds the bolt in the unarmed or safe position with the primer detonator 13 at one side of the axial passage 10 and out of line with the firing pin and a charge 16 in the lower or inner part of 40 the axial passage. A spring 17 confined between the bolt and a plug 18 threaded to the body 5 serves to move the bolt to the armed position when the firing pin is withdrawn so as to position the primer detonator 13 axially of the fuse and 45 between the firing pin and charge 16.

The front part of the body 5 is formed with a cavity 19 for receiving an inverted cup 20 to which the firing pin 15 is attached. A spring 21 surrounding the firing pin and confined between 50 the floor of the cavity and the closed front end of the cup normally tends to move the cup to an extruded position and thereby withdraw the firing pin from the aperture 14 of the bolt 12 and place it in armed or firing position. A flange 22 55 on the inner end of the cup 20 serves as a guide

and is adapted to engage a ring 23 fixed in the mouth of the cavity to limit extrusion of the cup.

The cup 20 is normally held in firing position within the body 5 and against the action of the spring by means of a cap 24 which is threaded on the reduced front end 25 of the body. The cup 20 is of a predetermined height to maintain a clearance 26 between the cap and the shoulder of the body and thereby prevent jamming and assure rotation of the cap. A propeller 27 is secured to the front face of the cap by means of rivets 28.

The fuse is safe when the parts are in the relation shown in the drawing, the cap 24 holding the firing pin 15 in the bolt 12. When a projectile carrying the fuse is fired from a mortar the propeller is rotated by the air and the cap 24 is unscrewed from the fuse body 5. The cup 20 carrying the firing pin follows the cap under the influence of its spring until arrested by the ring 23. The bolt 12 moves to armed position so that on impact the firing pin will be driven into the primer detonator 13.

The threaded connection between the cap 24 and fuse body 5 is of sufficient length to prevent removal of the cap while the fuse is in the bore of the gun.

I claim:

1. A fuse including a body having a reduced front end with a cavity, an inverted cup in the cavity and having a flange on its inner end, a spring normally tending to move the cup to an extruded firing position, a ring fixed in the mouth of the cavity and limiting movement of the cup, a firing pin fixed to the cup, a cap threaded on the reduced front end of the body and holding the cup in retracted position within the cavity, a propeller on the cap, a bolt mounted in the body for sliding movement transversely thereof, a primer detonator in the bolt, a spring for moving the bolt to armed position, said bolt normally held in unarmed position by the firing pin when the cap is in place on the fuse body.

2. A fuse including a body, a firing pin in the body, a spring, normally tending to move the firing pin to an extruded firing position, means for limiting extrusion of the firing pin, a cap threaded on the front end of the body and holding the firing pin in retracted position, a propeller on the cap, a bolt mounted in the body for sliding movement transversely of the firing pin, a primer detonator in the bolt, a spring for moving the bolt to armed position, said bolt normally held in unarmed position by the firing pin when the cap is in place.

3. A fuse including a body, a primer detonator carrier in the body, a firing pin in the body and normally holding the carrier in unarmed position, a cap threaded on the body and removable during flight, said cap holding the firing pin to maintain the carrier in unarmed position, and means for moving the firing pin to release the carrier when the cap is removed.
4. A fuse including a body having a cavity in its front end, an inverted cap in the cavity and having a flange on its inner end, a spring normally tending to move the cup to an extruded firing position, a ring fixed in the mouth of the cavity

and limiting movement of the cup, a firing pin fixed to the cup, a cap threaded on the front end of the body and holding the cup within the cavity against the action of its spring, and means on the cap whereby the cap is removed during flight. 5

5. A fuse including a body, a firing pin in the body, a spring normally tending to move the firing pin to an extruded firing position, a cap threaded on the body and removable during flight, said cap holding the firing pin against the action of its spring. 10

HAROLD G. TOWNER.
